SEWING MACHINE

Thomas E. Monroe, New York, N. Y., assignor of one-half to William R. Donaldson, Northport, N. Y., and one-fourth to William R. Donaldson, as trustee; William R. Donaldson administrator of said Thomas E. Monroe, deceased

Application February 2, 1943, Serial No. 474,451

32 Claims. (Cl. 112—98)

1

This invention relates to sewing machines.

It is an object of the invention to provide a machine which produces a chain stitch having improved locking characteristics.

It is a further object of the invention to provide a machine which produces such a stitch in which the loops of the successive stitches are of varying lengths.

It is a further object of the invention to provide improved mechanism for producing a multiple chain stitch, or stitch in which the successive loops are taken from different threads.

It is a further object of the invention to provide a machine which, without sacrificing simplicity and reliability of construction and operation, provides a considerable range of variations in stitch sequence and in stitch length.

Still another object of the invention is to provide improved fabric feeding and thread handling mechanism for sewing machines.

In certain aspects, as will appear more specifically in the following description, the present invention constitutes an improvement upon the disclosures of my previous patents, Nos. 2,152,203, issued March 28, 1939, and 2,206,484, issued July 2, 1940 and my patent applications Serial No. 322,867, filed March 8, 1940, and Serial No. 373,976, filed January 10, 1941, as a division of the last mentioned application. Both of those applications were co-pending with the instant application and were abandoned after the filing of patent applications Serial No. 559,580 and Serial No. 559,579, both filed October 20, 1944, as continuations respectively of the two first mentioned applications and both co-pending with the instant application.

The claims of the present application are directed to the machine disclosed herein, the improved methods of stitching forming the subject matter of my application Serial No. 474,450, filed February 2, 1943, for Stitch and method of stitching.

With the foregoing general objects in view and still others which will appear in the following full description, the invention consists in the combinations and arrangements of parts and details of construction which will now be fully described in connection with the accompanying drawing and then more particularly pointed out in the appended claims.

2

In the drawing:

Figure 1 is an elevation view of a sewing machine embodying the invention in a preferred form, and is taken looking forwardly or in the direction of fabric advance, certain casing parts having been broken away to show internal mechanism;

Figure 2 is an enlarged view of a thread feeder or looping member of the machine in Figure 1 together with certain associated operating mechanism therefor;

Figure 3 is a vertical cross section taken on the line 3—3 of Figure 1;

Figure 3A is a detail plan view of the needle hole;

Figure 4 is a plan view of the control mechanism shown in Figure 3;

Figure 5 is an enlarged cross section taken on the line 5—5 of Figure 4 and showing certain adjustable cam mechanism for controlling the operation of the thread feeding mechanism;

Figure 6 is an enlarged cross section taken on the line 6—6 of Figure 4 and showing the drive mechanism for the needle-bar and feed-foot bar of the machine;

Figures 7 and 8 are detail cross section views of a hollow shaft shown in Figure 6 and showing sections thereof where the same is cut out to accommodate certain regulating mechanism 30 by means of which stitch length is controlled;

Figure 9 is a section taken on the line 9—9 of Figure 3 and showing the regulating mechanism for varying the stitch length;

Figure 10 is a view on an enlarged scale of a portion of Figure 1, and with parts removed so as to show more clearly a portion of the drive mechanism thereof for operating the needle-bar and feed-foot bar and for controlling the thread feeding mechanism;

Figure 11 is a view similar to Figure 10 but with parts removed so as to show the main worm drive and one-way clutch of the machine;

Figure 12 is a view in exploded perspective of the parts of Figure 10 which comprise the adjustable cam for controlling the thread feeding mechanism;

Figures 13 and 14 are views showing this adjustable cam in the position of Figure 10 but illustrating two different conditions of adjustment;

Figure 15 is a view looking in the direction of the line 15—15 of Figure 3 and showing further the mechanism for regulating stitch length and for producing varying length stitches;

Figures 16 and 17 are respectively plan and section views showing schematically a double chain stitch such as may be produced from two threads by the machine of Figure 1;

Figures 18 and 19 are similar views showing an alternative stitch producible by the machine and in which three successive loops are taken from one thread for every loop taken from the other;

Figures 20 and 21 are views showing a single chain stitch which may also be produced by the machine;

Figure 22 is a section view similar to Figure 17 but showing a double chain stitch with varying length loops;

Figure 23 is a view similar to Figure 21 but showing a single chain stitch with varying length loops;

Figures 24 to 27, inclusive, are schematic views on an enlarged scale taken on the line 24—24 of Figure 1 and showing different positions of the thread feeding and looping mechanism;

Figures 28 to 31, inclusive, are schematic views showing the cam and pin drive mechanism for the needle-bar and feed-foot together with the lower portions of the needle-bar and feed-foot and showing the motions of these parts corresponding to the movements of the cam;

Figure 32 is a view similar to Figure 2 but showing a modified form of looping member adapted to handle a plurality of threads in each loop;

Figure 33 is a view similar to Figure 3 but showing only the lower part of the machine and showing a modification thereof for handling pluralities of thread in each loop and which is used with the modified looping member of Figure 32;

Figure 34 is an enlarged front elevation of the lower end of the needle of Figure 1;

Figure 35 is a side elevation of the lower end of this needle;

Figure 36 is a cross section of the needle of Figure 34 taken on the line 36—36 of Figure 34;

Figure 37 is an enlarged view of a modified stitch control mechanism which may be substituted for that of Figure 10;

Figure 38 is a view of the mechanism of Figure 37 with a cover plate removed and is a section taken on the line 38—38 of Figure 40;

Figure 39 is a view similar to Figure 38 but with further parts removed; and

Figure 40 is a section taken on the line 40—40 of Figure 38.

Frame structure and drive mechanism

Referring now to Figure 1, the machine of the invention will be seen to be generally C-shaped, comprising a split casing having a lower section 1 and an upper section 2 joined together by flanges 3 and 4 and mounted on a base 5. The lower terminal of the C forms a housing 6 for the thread feeding and looping mechanism and the upper terminal forms a housing, designated generally as 7, for the needle-bar and feed-foot operating mechanism.

The machine drive comprises a motor 8 mounted in the casing and having a shaft 9 terminating in a worm 10 and journaled in a bracket 11 forming part of an inner supporting frame 12, which is removably fastened to the casing member 1 as by means of screws 13—13 located at convenient points. As will appear later, the major part of the operating mechanism in the upper housing 7

or head 7 is carried on this frame 12 and may be readily removed therewith.

The main drive shaft for the machine comprises a hollow outer shaft 14 and solid inner shaft 15 (Figures 4 and 6) driven by worm 10 through worm wheel 16. As best shown in Figures 6 and 11, the worm wheel 16 includes side bearing plates 17 within which is carried a one-way clutch, comprising a central clutch member 18 and clutch balls or rollers 19 carried in notches formed in the periphery of the member 18, as shown. The inner surface of the rim of the worm wheel 16 forms a raceway so that, as will be understood, the worm 10 will drive the shafts 14—15 in one direction (clockwise in Figure 11) but not in the other. By this means manual turning of the main shaft without turning the motor shaft 9 is provided for. The main drive shaft 14—15, as best shown in Figure 6, is carried in a bearing 20 which is mounted on the frame member 12 and extends through the casing section wall 7. A fly wheel 21 on the end of the shaft 14 outside the casing 7 is fastened to a hollow wheel housing 22 within which and upon which are provided certain arrangements, later to be described, by means of which the angular relationship of the outer shaft 14 and inner shaft 15 may be varied or set as desired within certain limits.

The opposite end of the main drive shaft 14 carries, adjacent the worm wheel 16, a drive pinion 23 for the thread looping operating mechanism, later described, and also a drive cam 24 which, as best shown in Figures 6, 8 and 10, is bifurcated and passes through opposed slots 25, 26 in the hollow shaft 14, being fixed in position by cooperating rack teeth 27 formed on one side of the cam slot and a pinion 28 formed on the end of the inner or solid shaft 15, which is in mesh with the rack teeth 27. As will be observed, turning of the inner shaft 15 with relation to the outer shaft 14 will, by means of the rack and pinion 27, 28, result in moving the cam crosswise of the main shaft. For the present, however, the cam and shaft will be supposed to be in set or fixed relation.

Feed-foot drive

The cam 24 fits within a follower head or yoke 29 which is formed on the top of feed-foot plunger 30 and bears a drive pin 31 which operates the needle-bar 32 by means of a mutilated yoke 33 formed at the top thereof (Figure 1). The cam 24 comprises, as indicated in Fig. 28, opposed high and low portions constituting dwell portions W and X which occupy approximately 120° each and which are separated by feed-foot depressing and elevating portions Y and Z each occupying about 60°. The cooperating surfaces, by means of which the follower 29 is driven by the cam to raise and lower the feed-foot plunger, include, as shown in Figure 10, spaced slanted straight portions engaging opposite portions of the cam.

Needle-bar drive

The drive pin 31 for the needle-bar is angularly related to the rise and fall portions of the cam 24 so as to produce a desired cycle of operations, 70 as more fully described below, in proper relation to the movements of the feed-foot.

At this point it is necessary to note that, starting in the position of Figure 1 which represents a position where the parts are at their highest 75 position, the rotation of pin 31 carried by cam

24 will produce little or no movement of needle-bar 32, due to the fact that pin 31 (moving counterclockwise) will be in an approximately concentric slot 34 in the yoke 33. This movement may continue for approximately 120°. Thereafter, further movement of the pin 31 forces the yoke 33, and needle-bar 32 to which it is attached, downwardly through about 120°, and further rotation lifts the yoke, returning it to the position of Figure 1. The lower wall of the yoke slot 34 is broken or mutilated as shown and an open space 35 is provided therebelow. By this means it is possible, when the parts are in the position shown in Figure 1, to lift the needle-bar 32 manually, the pin 31 being received within the open space 35. Should operation be attempted in this condition, the pin 31 will merely rotate idly within the open space 35 which is made large enough to accommodate such rotation. In order to prevent possible jamming when the needle-bar is inadvertently left in such raised position the dividing wall 36, which separates the opening 35 from the slot 34, is formed with a pointed end as shown so as to insure that the pin 31, should it engage the same, will pass either into the driving slot 34 or into the idling space 35.

Feed-foot bar and needle-bar construction and mounting

As best shown in Figures 1 and 3, the feed-foot operating member or bar 30 and the needle-bar 32 are carried in openings or cutouts formed in a pair of brackets 37, which extend outwardly from the support frame 12 previously referred to, and pass through an opening in the bottom of the upper housing 7. The feed-foot bar 30 carries, by means of a spring 38 and pins 39, a bifurcated feed-foot 40 which is formed with a rearward wall 41 for engaging the spring 38 and with angularly disposed slots 42 in its side walls for receiving the pins 39. Only one side of the feed-foot bar is shown in Figure 3, but, as will be understood, an identical slot 42 and pin 39 are located on the opposite side.

The lower end of the feed-foot member 40 is formed with teeth, as shown, for engaging the fabric. The needle-bar 32 carries a hooked needle 43 in a slot 44 at its lower end, the needle being fastened therein as by means of a retaining member 45 and set screw 46.

Cooperating with the hooked needle 43 is a needle pin 47 more fully described below and which terminates in a T-head 48 which is accommodated by a cutout 49 in the needle-bar as shown in Figure 3. The projecting T-head is engaged by spring tongues 50 at either side of the needle bar, which urge it outwardly, and cooperates with an abutment 51 and recess 52, which are conveniently formed by stamping the metal of the housing wall to form the abutment 51 and also a projecting tongue or abutment 53 below the recess 52. By means of this mechanism, the needle pin will be held back by the T-head 48 engaging against the projection 51 when the needle-bar descends. As the needle-bar passes still further downward, the upper wall of the cutout 49 engages the T-head, forcing the same over the projection 51 and into the recess 52. When the needle-bar rises again the T-head will be held within the recess 52 until the lower wall of cutout 49 has engaged it, after which time the needle pin will be raised by the needle bar. In this way the opening and closing of the needle hook is properly related to the cycle of operations of the needle.

The needle-bar may be raised manually when required, housing 7 being provided, for this purpose, with an opening 55 which accommodates a handle 56 fastened to the needle-bar 32.

Fabric-foot and fabric table construction

A fabric-foot 57 is provided, including pressure tongues 58 at opposite sides of the feed-foot and is slidably mounted on a member 59 which is attached to the housing wall by screws 60 and is urged downwardly by a spring 61. These various parts cooperate with the fabric table 62 which forms part of the lower housing 6 and with a needle hole 63 at the edge of the fabric table 62. 15 Beyond the needle hole 63 the casing of the lower housing 6 forms a downwardly slanted surface 64. The fabric motion will be along table 62, from right to left in Figure 3, over needle hole 63 and then downwardly along the surface 64. The needle hole 63 is conveniently formed with a round portion 65 located at the edge of the table 62 and a slot 66 extending a small distance down the slanted surface 64. The edge of table 62 adjacent the needle hole 63 is advantageously given 20 a slight inclination or slant downwardly toward the slanted surface 64 for reasons pointed out below.

The fabric-foot mounting just described possesses considerable advantages over those conventionally employed. Due to the slant of member 59, the precise amount of which is not critical but which may be about 45°, the fabric-foot will resist strongly any force which tends to raise it vertically, and accordingly will function efficiently

30 to hold the fabric down against any upward pull by the needle. However, the force of any extra thickness of the fabric as it engages under the upwardly curved ends of the fabric-foot tongues 58 in its motion across fabric table 62 will be exerted 35 in approximate alinement with the member 59, facilitating the raising of the fabric-foot to accommodate irregularities such as extra plies in the fabric being sewn. Such fabric-foot mounting is also found advantageous in conjunction with a fabric feed member which operates on the same side of the fabric, as in this case the fabric may be backed up by the solid fabric table so as to give the required grip to the feed member, and heavy pressure of the fabric-foot is unnecessary.

Operating cycle of the needle-bar and feed-foot bar

Starting in the position of Figures 1 and 28 55 rotation of shaft 14—15 will, by means of cam 24 and pin 31 perform the following cycle of operations:

Rotation to the position of Figure 29, through 60 30 to its lowermost position or to the position of approximately 60°, will lower the feed-foot bar Figure 29, as the rise Y of the cam is in contact with the lower wall of the follower slot. In this position the feed-foot 40 is resting upon and is supported by the fabric, a slight upward movement of the feed-foot 40 on the bar 30 being provided for by means of the slot 42. During this time the needle-bar will have remained substantially stationary, although it may move slightly upwards and then return to its starting position 65 as indicated in Figure 29.

During the next 120° of revolution of the cam 70 the needle descends to its fullest extent and the beveled lower edge 67 of the needle-bar will slide down the slanted portion 68 of the feed-foot, wedging the same aside as indicated in Figure 30

and imparting the desired movement to the fabric just prior to the needle entering the same. During this movement the dwells **W** and **X** of the cam will be in contact with the follower walls so that the feed-foot bar remains stationary. Continuing movement of the cam **24** brings the parts to the position of Figure 30, the needle-bar having almost completed its stroke. At or shortly after this point the feed-foot commences to rise. Further rotation continues to move the needle slightly downward until the pin **31** has reached its lowest point.

Rotation through another 60° will raise the needle-bar and feed-foot simultaneously to the position of Figure 31, and further rotation will restore the parts to the position of Figures 1 and 28 in preparation for another stitch.

Feed-foot construction and operation

By means of the pin-and-slot mounting described above the feed-foot **40** is carried by the bar **30** both slidably and pivotally, and the resulting freedom of movement permits it to find its position with reference to fabric on the table **62** and also with reference to the needle-bar **32** so that substantially the same feeding movement is imparted to fabrics of different thicknesses.

The angle, **U**, of slant of the feed-foot portion **68** and the angle, **V**, of slant of the slots **42**, will preferably be equal as indicated in Fig. 28. In this way, the feed-foot may best accommodate itself to varying thicknesses of fabric while maintaining the proper relationship with the needle-bar. As will be understood, the presence of fabric in the machine will alter the position of the feed-foot in Figure 29, this member coming to rest in a higher position, so that pins **39** are not so near the upper ends of slots **42**. However, completion of the movement of the feed-foot bar **30** will, through pins **39** riding in slots **42**, force the upper end of the feed-foot **40** toward the needle-bar **32**, thus causing the lower end of the feed-foot to move back in the fabric feeding direction. The fabric feeding movement will then be completed by the needle-bar acting against the slant **68**. In this way, substantially the same length of feed of the fabric, regardless of thickness, may be obtained. Where, however, the stroke of the feed-foot bar **30** is altered, as described below, the lowermost position of pins **39** will be changed and the desired change in length of stitch obtained.

The slight inclination of the fabric table forwardly adjacent the needle hole **63**, which was referred to above, is designed to assist the action of the feed-foot by furnishing a surface with which the lower side of the feed-foot is in substantial parallelism when the material being sewn is of about the maximum thickness that the machine will accommodate as indicated by the distance between the inclined portion of the fabric table and the feed-foot as seen in Fig. 28 or Fig. 31, and with which the lower side of the feed-foot approaches substantial parallelism as it swings rearwardly in a fabric feeding direction to the position of Fig. 30 when the material being sewn is relatively thin. Inasmuch as the pins **39** are spaced horizontally from the line of movement of the needle in the construction illustrated, this results in an inclination of the fabric table forwardly adjacent the needle hole. However, a construction in which the pivotal axis of the feed-foot is placed over the needle hole would require a horizontal surface for the best

action of the feed-foot, the important characteristic being the substantial parallelism of the surface with the lower side of the feed-foot as it swings to its rearward position about its pivotal axis.

Thread handling and looping mechanism

Thread is fed to the needle below the table **62** by a thread feeder or looping member **69** and associated mechanism. As shown in Figure 1, a support **70** having spindles **71** for a pair of spools is provided and, as indicated in Fig. 3, threads from the spools are conveniently tensioned by weighted members **72** pivotally carried at **73** on the lower housing walls. The degree of tension provided may be controlled by means of weights **74** mounted on arms **75** which are pivotally carried upon the members **72** at **76**, so that the distance of a weight **74** from the corresponding pivot **73** may be varied, as desired, by turning the arms **75**.

The looping member **69** (Figures 1, 2 and 24) is formed at its upper end with a needle engaging surface **77**, to each side of which are positioned thread guiding holes **78**, and with wing portions **79** for insuring that the looping member will engage the needle properly. Below this upper end the looping member **69** is pierced as at **80** to permit ready stamping and is formed below the piercing **80** with a reversely facing angular abutment **81** which cooperates with operating mechanism about to be described. The shank **82** of the member **69** includes a relatively short portion **83** which is twisted at right angles, and fastened at its lower end **84** by means of a screw **85** to a bracket **86** upon the machine base. The shank of the member **69** is preferably of springy material and will have relatively large flexibility in its front and rearward movement, and be relatively stiff in its sidewise movement, due to the fact that twisted portion **83** is short relative to the shank generally.

Means for operating the looping member **69** is provided (Figures 1, 3 and 24 to 27) and comprises a slideable actuating member **87** formed with an angle **88** adapted to engage and receive the angular abutment **81** previously referred to, and which is carried in brackets **89** attached to a support plate **90**. The support plate **90** includes a portion **91** against which the upper end of the member **69** may slide and is provided, to each side of this portion, with stops **92** for limiting movement of the member **69**. The respective threads **A** and **B** pass from the spools through the guiding holes **78** of the looping member **69** and, as indicated in Figures 24 to 27, movement of member **87** operates the thread feeding mechanism in the following way:

Starting in the position of Figure 24 which is the center or feeding position, the angle **88** and thread looping member **69** will be located directly under the needle, which is indicated in phantom. As the needle completes its rise from the previous stroke the member **87** moves to the left, forcing the looping member **69** forwardly against the surface **91** and sidewise along the same to the position of Figure 25. Due to the greater flexibility of the shank **82** in that direction, the motion will be principally forward until the member **69** engages the surface **91** and the greater part of the sidewise movement will take place after such engagement. This movement brings both threads to the left side of the needle. When the needle has descended, member **87** returns to center position, which permits member **69**, due to the spring-

iness of its shank, to return to center position likewise, so that the nearer or righthand thread may be forced by the needle against the needle engaging surface 17. Upward movement of the needle will now engage or wipe the thread into the hook where it will be held by the needle pin, until the next stitch.

In the next cycle of operations, the loop previously formed will be released and, starting again at the position of Figure 24, the parts will move in the opposite direction so as to occupy the position of Figure 27 rather than Figure 25. Thereafter the parts will return again to the position of Figure 26 with the result that a loop is formed from the other thread. In this way a double chain stitch such as shown schematically in Figures 16 and 17 may be formed.

Thread handling drive mechanism

The member 87 includes an extension 93 (Figure 1) which is pivotally connected to one end of a bell crank 94, which in turn is carried by a pivot 95 and urged to the right by a spring 96. To the other arm of bell crank 94 is pivotally connected a cam rod 97 which is slidably carried by a bracket 98 formed on the frame member 12 and which terminates in an abutment 99 and pin 100 extending therefrom. A cam follower 101 is carried on a pivot 102 upon the frame member 12 and comprises a follower portion 103 and an end 104 which engages the abutment 99 and which is provided with an opening receiving the pin 100.

Mechanism for driving the member 87 through the arrangement just described is provided, and is carried on a stub shaft 105 (Figures 4 and 5), mounted on the frame 12 as indicated, and which includes a collar 107 for retaining it in longitudinal position and a reduced portion 108 which passes through and supports the rotatable shaft member 109.

Keyed to the hub of shaft member 109 are a gear wheel 110 in mesh with the drive pinion 23 previously referred to and a fixed cam member 111 which is fastened to the gear wheel 110 as by means of pins 112. The cam member 111 comprises high portions H, middle portions M, and low portions L (Figure 12) forming three levels for engagement by the cam follower 101 and corresponding to the three positions of the operating member 87 previously referred to. The cam assembly includes also a pair of adjustable cam members 113 and 114 which are likewise mounted upon the shaft member 109 and each of which has a single high level with adjacent rise and fall portions (Figure 12). By adjusting the members 113 and 114 relative to the member 111, the cam action can be varied as more fully described below. For carrying out this adjustment a pair of arms 115 and 116 are provided, each of which carries a pin, 117 or 118, which is adapted to enter into an opening, 119 or 120, in the cam member 113 or 114, as the case may be. An adjusting wheel 121 is keyed to the end of shaft member 109 and is held on shaft 105 together with the cam assembly by means of a washer 122 and screw 123. As best shown in Figure 1, the wheel 121 is provided with four peripheral notches or indentations 124 and the ends of members 115 and 116 are bent over as indicated so as to provide tongues which are adapted to enter into these indentations and be held thereby.

By turning the members 115 and 116 relative to the wheel 121 and fitting the same in the various notches provided, the contour of the cam may be altered in the following way: With the parts

set in the position of Figure 1, which is the same as that of Figure 10, the high points of members 113 and 114 will be in registry with the high points of fixed cam member 111 and hence the operation of the cam will be the same as though members 113 and 114 had been omitted. In this case each revolution of the cam will bring a high, low, high and low level successively in contact with the cam follower 101 so that a movement 10 of the cam follower from one extreme position to the center position, and then to the other extreme position will occur in each half revolution of the cam. As will be understood the successive high or low levels are in all cases separated by middle levels. Full revolution of the cam will accordingly produce four complete looping movements of the cam follower, and accordingly the gear ratio of drive pinion 23 and gear wheel 110 is made 1 to 4 so that cam shaft 109 will rotate at one quarter the speed of the main shaft.

Starting in the position of Figure 10 which represents the parts in their positions when the needle-bar and feed-foot are at the top of the stroke, the rotation of the main shaft through a full revolution completes a cycle of stitching operations of the feed-foot plunger 30 and needle-bar 32, but pinion 23 produces a quarter revolution of the cam 111 so that the follower passes from a high level to a middle level and then to a low level. In this way the cycle of operations of member 87 is carried out and proper synchronism of its movements with those of the feed-foot plunger 30 and needle-bar 32 is obtained.

If it is desired to take a succession of three loops from one thread for every loop taken from the other, one of the members 113 or 114 may be turned through 90° as shown in Figure 13. In this case, the cam contour consists of three successive high levels and one low level, each of course being separated from the others by middle levels. Accordingly the member 87 will be moved into the position of Figure 25 three times in succession and then into the position of Figure 27, so that three successive loops will be taken from one thread for each loop that is taken from the other, making the stitch shown in Figures 19 and 20.

By setting both members 113 and 114 as indicated in Figure 14 the cam contour is modified so that it has only high and middle levels and accordingly thread will be taken from only one spool, resulting in a single chain stitch as indicated in Figures 20 and 21.

Stitch length variation

Means is provided for varying the length of stitch for the successive loops, and constitutes an important feature of the present invention by means of which desirable locking characteristics are obtained, and by means of which very pleasing decorative effects may also be obtained particularly when employed in conjunction with alternation of threads in the successive stitches. This means includes a control mechanism for rotating the inner or solid main drive shaft member 15 in relation to the outer or hollow main drive shaft member 14, so that the cam 24 is displaced by means of pinion 28 operating upon rack 27. The angular adjustment of shaft 15 is accomplished through a slotted arm 125 (Figure 6), the end 126 of which is fastened to the inner shaft member 15. Outer shaft member 14 is slotted as indicated in Figures 6 and 7 to accommodate angular movement of the arm 125. Movement of arm 125 is controlled with refer-

11

ence to the fly wheel housing 22 by mechanism about to be described.

At this point it should be noted that, when the housing 22 is fixed in relation to fly wheel 21 and the arm 125 is in turn fixed in its relation to the housing, the shafts 14 and 15 will have at all times a fixed relationship and, accordingly, the relationship of cam 24 to the main drive shaft will be fixed and a fixed length stitch will be provided. To permit adjustment of the stitch length in general, a movement of housing 22 relative to fly wheel 21 is provided for, the latter being furnished with a series of indentations 127 and the housing 22 carrying a member 128 having a corresponding projection 129 which is adapted to enter into the indentations 127. By this means the housing 22 may be turned relative to fly wheel 21 and set in any of a number of desired angular positions. Assuming arm 125 to be fixed in relation to the housing 22 this will accomplish the necessary angular adjustment of shafts 14 and 15 for changing the length of stitch.

Mechanism is provided by means of which arm 125 may be fixed in its relation to housing 22 and also for varying its relation to housing 22 so as to produce a sequence of stitches of varying length. This mechanism includes, as best shown in Figures 6, 9 and 15 a fixed gear 130 which is formed on the end of the bearing member 20, previously referred to, and cooperating gears 131 and 132, forming a planetary train, and the latter of which carries a pin 133 which operates in the slot of the arm 125 previously referred to.

Gear 132 is rotatably carried on a shaft 134 which is mounted on the housing 22 and gear 131 is rotatably mounted upon a shaft 135 which is carried by an arm 136 which, in turn, is pivotally mounted upon shaft 134. Gears 131 and 132 are always in mesh but gear 131 may be put into mesh or out of mesh with the fixed gear 130 by adjusting the arm 136 to the proper one of the two positions indicated in Figures 9 and 15. The parts are held in these positions by a projection 137 upon the arm 136 which may fit in either of two indentations, 138 or 139, upon the wall of the housing 22. Movement of the shaft 135 during this adjustment is provided for by a slot 140 in the wall of the housing member 22 and rotation of the gears 131 and 132 when in the position of Figure 9 is prevented by a pin 141 which is carried by the housing 22, as shown.

As will be apparent, with the parts in the position of Figure 9 the relationship of slotted arm 125 to housing 22 is fixed due to the fact that pin 133, which engages in its slot, is fixed in position through the teeth of gear 132 in mesh with gear 131 which in turn is held from turning by the pin 141. If, however, arm 136 is turned so as to bring gear 131 in mesh with fixed gear 130, the position of arm 125 with relation to the housing 22 will no longer be fixed but the arm 125 will be rocked back and forth by pin 133 as the gears rotate. In the construction shown, gear 131 has a 1 to 1 drive ratio with the fixed gear 130 and hence will make one complete rotation for each complete rotation of the main drive shaft and housing 22. The gear 131 has, however, a 1 to 2 drive ratio with the gear 132, which accordingly will make a half rotation for each rotation of the main drive shaft and housing 22. It should be noted, in this connection that the position of the gear 132 relative to the rotating shaft 15 rather than to a stationary part is the determining factor in the production of the rocking movement. Accordingly, a complete ro-

12

tation of the main drive shaft and housing 22 will restore the parts to the position of Fig. 15 but the pin 133 will be on the opposite side of shaft 134 and the arm 125 will be rocked accordingly. A second complete rotation of the main drive shaft and housing 22 will restore the parts to the previous position of Fig. 15. When it is borne in mind that rocking of shaft 15 relative to shaft 14 moves the cam 24 so as to vary the stitch length, it will be apparent that the stitch length on the even numbered rotations of the housing will be increased from that which occurs when the arm 125 is in the position of Figure 9 relative to the housing 22. In this way the stitch of Figure 22 may be formed, the thread feeding cam having been set as in Figure 10 so that stitches are taken alternatively from the two threads. By setting the member 128 for a short stitch and the arm 136 for stitches of varying lengths, and assuming the parts to be in the position of Fig. 15, the machine will produce at the first revolution of the main drive shaft a short loop as shown. When, however, this loop has been completed the arm 125 will have rocked (to the left in Fig. 15) and the next stitch taken from the other thread will be a long loop as shown. The longer length of stitch is composed, in effect, of the set stitch length and the increment resulting from angular rocking of shaft 15 with relation to shaft 14, by means of which the cam 24 has been set further out for the making of this stitch. Since the parts now return to their original position the next loop will be a short loop formed from the first thread and in this way a succession of alternate short and long loops formed from the respective two threads will be obtained. Wide variation in the varied length stitches is obtained by adjusting for a desired eccentricity of the drive member and then rocking the inner shaft 15 to vary this eccentricity between predetermined limits.

If desired, the thread feeding cam may be set as shown in Figure 14 and in this case a stitch such as shown in Figure 23 will be produced, consisting of a single chain stitch having its alternate loops of different lengths.

Setting the thread feeding cam to the position of Figure 13 will result in a composite stitch in which the alternate loops are long and short and in which three loops are taken successively from one thread and one from the other. As is apparent, this setting will result, for example, in a short white loop followed by two long white loops and then by a long colored loop and again by a short white loop and so on. Alternatively, a long white loop followed by a short white loop, a long white loop and a long colored loop may be obtained. These stitches, the formation of which will be evident from Figures 22 and 23, are not illustrated.

The formation of feed-foot drive cam 24 constitutes an important feature of the present invention and involves provisions for maintaining a sufficiently constant advance of the feed-foot movement with relation to the needle-bar movement while varying the stitch length (which depends upon the feed-foot movement) and the loop length (which depends upon the needle-bar movement) simultaneously so as to increase or decrease the stitch length and loop length in substantially the same proportion.

As will be apparent to those skilled in the art, those machines in which the tension mechanism permits stitch length variation by merely varying the fabric feed will not require any variation

in stroke of the needle-bar to produce the varied length stitches. Alternatively, machines having tension regulation suitable therefor may be adapted to produce the varying length stitches by varying only the stroke of the needle-bar. In view of this, the simultaneous regulation of fabric feed and needle stroke, while preferred, is not essential to the practice of the invention in its broader aspect.

As will be observed, when the shafts 14 and 15 are adjusted so as to increase the eccentricity of the cam 24 (by moving the same upwardly when in the position of Figure 10) the distance of pin 31 from the center of rotation is increased substantially proportionately. On the other hand, the angle of advance of the cam high dwell ahead of the pin 31 is diminished only slightly and any effect thereof upon operation of the machine will be negligible. In this way, the fabric feed is automatically adjusted, by controlling the height of the feed-foot carrying pins 39 at the end of the down-stroke of the feed-foot bar, so as to increase or decrease the fabric feed proportionately, while the proper advance of the feed-foot movements over the needle-bar movements is maintained. In the construction shown, suitable stroke variation is also imparted to the needle-bar.

The improved locking characteristic of the varying length stitch produced by the described mechanism will be apparent from Figures 22 and 23. In either case when it is attempted to separate plies of fabric which have been stitched together, a short loop (white loop in Figure 22) will be pulled through the fabric until its bend or tip is about to pass through. It is however, impossible for this to occur without the loop being freed of the long loop which passes through it, and this longer loop will lie across the fabric preventing the short loop from passing through in much the same fashion as would a pin, if passed through the short loop. This effect is, of course, not obtained with a chain stitch having loops of equal length as the loops are able progressively to free each other by successively falling back. While the best locking effect will be obtained by alternating the short and long loops, and by making the short loops as short as possible and the long loops as long as possible for a given average length of stitch, this is not essential for practicing the invention in its broader aspect, as sufficient locking effect for many applications may be obtained by using shorter and longer loops of various lengths in various sequences.

Construction of feed-foot drive cam

The cam 24 may be regarded as a modified eccentric having dwells during which substantially no movement of the follower is produced. As will be apparent, this is only substantially true, but may be made sufficiently true so that the desired operation is not interfered with.

The cam comprises opposite high and low arcs W and X (Figure 28) each of which occupies approximately a third of the circumference, or about 120°, and which are connected by respective rise and fall arcs Y and Z each of which in turn occupies approximately one sixth of the circumference, or about 60°. The arc W may be developed as a dwell concentric about an arbitrary center and the arc X will have its points equidistant from this arc when measured along diameters through the arbitrary center. This insures, during the rotation of the cam with its high and

low dwells in contact with the straight sides of the follower slot, that relatively close engagement without undesired play may be obtained. The rise and fall portions Y and Z are symmetrical about a line through the centers of the dwells and are determined so as to maintain the same distance between points which are opposite with relation to the arbitrary center referred to. In this way, close engagement of the cam with the follower at all angular positions is provided for.

As will now be apparent, the dwells cannot be precisely concentric about the center of rotation of the cam when the cam is in its various positions which are provided for adjusting the stitch length in general or for producing alternate stitches of different lengths. It is found, however, that adjustment of the cam through the small distance which is necessary to give a relatively wide variation of stitch lengths will not disturb concentricity of the dwells sufficiently to be objectionably perceptible in the action of the machine. The drive pin 31 for the needle bar yoke is set upon the cam 24, as previously indicated, so as to interrelate the cycles of operations of the feed-foot plunger and needle-bar in the desired way. In the type of construction illustrated, this may involve setting of the pin approximately 90° behind the commencement of the high dwell of the cam. The incline of the straight sides of the cam follower slot is provided for the purpose of properly correlating the needle-bar and feed-foot movements. The pin-and-yoke drive used for the needle-bar requires that the drive pin 31 operate in a dwell during approximately the upper third of its rotation. The advance of cam 24 with relation thereto must however be set within certain angular limits in order to provide for the adjustment referred to above. When this has been done, an inclined follower surface will be found necessary, as the feed-foot bar movements produced by a horizontal yoke would not be sufficiently early with relation to the needle-bar movements.

The cutting out of a portion of the low dwell X of the cam to form the adjusting slot therein has been found not to result in any appreciably objectionable play. In this connection it should be observed that the high dwell drives the follower in both directions.

Recapitulating the operation of the feed-foot cam and cam follower and the needle-bar pin and yoke, respectively, it will be observed that the cam produces a downward movement of the feed-foot through about one sixth of the revolution, followed by a dwell through about a third of the revolution, by an upward movement through about a sixth of the revolution, and by another dwell in raised position through the remaining third of the revolution. This cycle therefore contains four phases. The needle driving pin, however, has only three phases of operation, having a dwell through about a third of a revolution, a downward movement through another third, and an upward movement through the remaining third.

As suggested above, the division of rotary movements into sixths and thirds is not exact and need not be so, but a discussion in round figures of the relation of the two movements and omitting small angular variations will serve to simplify the same. Recalling the lead of the cam high dwell as compared with the drive pin, and starting in the position of Figures 1 and 28, a complete cycle of movement may be analysed in

successive steps of one-sixth of a revolution, as set forth in the following table:

	Feed-Foot Bar Action	Needle-Bar Action
First sixth	Moves down to position of Fig. 29.	Stationary.
Second sixth	Stationary	Moves down, pushing feed-foot to position of Fig. 30, just before entering fabric, hook of needle opens due to T-head 48 holding back needle pin.
Third sixth	do	Moves down to position of Fig. 30, and needle pin moves down, just below fabric table 62.
Fourth sixth	Moves back up to position of Fig. 31 (or Fig. 29).	Moves back up to position of Fig. 31, and needle pin closes hook just before hook reaches fabric.
Fifth sixth	Stationary	Moves back up to position of Fig. 28, and feed-foot returns to position of Fig. 28.
Sixth sixth	do	Stationary.

Needle construction

The invention contemplates the use of needles generally similar to those of my patents and applications referred to hereinabove but embodying an improved form of pin for opening and closing the hook of the needle. As shown in Figures 34 to 36, the hooked needle is grooved so as to receive the needle pin and permit sliding thereof. The needle pin itself, however, instead of merely coming down on top of the point of the hook, is formed with a groove 150 adjacent its lower end and adapted to receive the barb or point 151 of the needle. The point of the needle is accordingly set back toward the central axis of the needle so as to be about one quarter of the general needle diameter therefrom. As shown in Figure 35, the hook of the needle is sufficiently recessed to provide a space 152 for receiving the thread, which may be secured or locked therein by the pin.

Modification of looping member to handle pluralities of threads

According to another form of the invention, each loop may be formed with a plurality of threads from separate spools. In this case the thread looping member 69 may be modified as indicated in Figure 32, in which corresponding parts are indicated by numerals similar to those of Figure 2, but increased by 100, so as to have two thread holes or guides 178 at each side of the needle engaging portion 177 instead of a single thread guide 78 as in the case of the embodiment of Figure 2. As shown in Figure 33 which reproduces a portion of Figure 3 and shows modifications therein, a second spool supporting member 170 and further tension members 172, etc., may be provided so as to furnish a thread A₁ in addition to the thread A. The thread A may go through a lower hole 178 and the thread A₁ through the one immediately above it. As will be understood, similar spools furnish threads B and B₁ for the holes 178 on the opposite side of the thread engaging surface 177.

With this construction very novel decorative effects may be obtained, one loop being formed for example of a red thread and a blue thread and the next of a yellow thread and a purple thread. Many other combinations will be apparent, and it should be noted that with this arrangement, as compared with possible alternatives, the position of the threads both in the loops and in the courses on the reverse side of the fabric will be the same

from loop to loop so that very pleasing and uniform effects may be obtained.

Modified drive for the thread handling mechanism

Greater variation in, or control of the order of, production of stitches from the threads than is provided for in the construction as heretofore described may be obtained by suitable modification of the operating mechanism.

One such modification, involving the substitution of other mechanism for the cam 111, is illustrated in Figures 37 to 40. Figure 40 is a view similar to Figure 5 but on an enlarged scale and showing modifications. As there shown, a shaft member 206, similar to the member 105 of Figure 5, is provided and carries a rotatable hollow shaft 209 generally similar to the shaft member 109 of Figure 5. A gear wheel 210 is provided for engagement with the drive pinion 23 and is similar to the gear wheel 110 except for modifications about to be described.

The operating structure carried on the hollow shaft member 209 comprises an inner disk 211, secured to the gear wheel 210 as by means of pins 212 and keyed to the hollow shaft 209, and also a cog shaped member 213, which is keyed to the hollow shaft 209, and provides surfaces M₁ serving as middle levels for engagement by a follower member 201 which is mounted on a pivot 202 and controls the movements of the rod 97 previously referred to. Four additional members 214 are provided and each is adapted to be adjusted so as to serve as either a high level or a low level for engagement by the follower member 201. Each such member comprises a short inner shaft 215, an eccentrically disposed intermediate portion 216 and a reduced outer shaft 217. The inner shafts 215 pass through keyhole openings 218 in the disk 211 and through circular openings 219 in the gear wheel 210 which latter openings serve as bearings. The reduced outer shafts 217 in turn are carried in openings 220 in a face plate 221 which is keyed to the hollow shaft 209. Each member 214 is urged, axially of shaft 209, toward the position of Figure 40 by a spring 222 thrusting against disk face plate 221 and carries an adjustment knob 223 positioned outside of the face plate 221.

Each cutout 218 in the disk 211 is shaped so as to receive the operative portion 216 of a member 214 and hold the same in an outward position (to right and left of Figure 38) or in an inner position (upper and lower positions of Figure 38 and position shown in Figure 40). The construction of the disk 211 is shown more clearly in Figure 39, which is similar to Figure 38 but in which the members 214 and 213 have been removed. By pulling out the knob 223 so as to release the member 214 from engagement in an opening 218, the member may be turned so as to present either a high or a low level to the follower and then allowed to return so as to seat in the opening 218 and be held in the desired position. The contour of the high levels H₁ is not critical as it is immaterial whether there is actually a dwell in the follower movement or not and the same is true of the low levels L₁.

The cam follower 201 may be constructed with a bearing surface E conforming to the tip radius of the member 213 so as to produce a dwell in middle position. The length of dwell, expressed angularly, will equal the angle subtended by the middle level M₁ added to twice the angle subtended by the follower engaging surface E. To each side of the

engaging surface E the follower member is formed with rise and fall surfaces R and F.

The structure just described provides for successive sequences of either high or low levels as desired and will produce the same operation as will structure of Figure 5 previously described. However, the structure of Figure 5 will provide only for adjustment to give four high levels, three high levels, or two high levels while the present structure will provide in addition for only one high level or for no high levels. Hence, while the construction of Figure 5 may produce only the stitch sequences AAAA; AAAB, ABAB (from two threads identified as A and B) the construction just described will produce in addition the sequences ABBB and BBBB. In addition, the modified construction will provide for the sequence AABB, which is not possible with the construction of Figure 5.

What is claimed is:

1. In a chain stitch sewing machine, and in combination, a hooked needle, a reciprocable needle-bar, means for reciprocating said needle-bar, thread handling mechanism cooperating with said needle for forming a loop at each reciprocation thereof, fabric feeding mechanism for feeding fabric past said needle at each reciprocation thereof, and automatic means for varying the length of stroke of said needle-bar at the successive reciprocations thereof to vary the length of loop.

2. In a chain stitch sewing machine, and in combination, a hooked needle, a reciprocable needle-bar, means for reciprocating said needle-bar, thread handling mechanism cooperating with said needle for forming a loop at each reciprocation thereof, fabric feeding mechanism for feeding fabric past said needle at each reciprocation thereof, and automatic means for varying the length of stroke of said needle-bar from a longer stroke to a shorter stroke in a predetermined sequence at the successive reciprocations thereto to produce longer and shorter loops in a predetermined sequence.

3. A sewing machine according to claim 2, comprising also manually adjustable stroke regulating means for regulating the lengths of said longer and shorter strokes.

4. In a chain stitch sewing machine, and in combination, a reciprocable needle-bar and a feed-foot, operating mechanism for reciprocating said needle-bar and moving said feed-foot, comprising automatic means for varying the length of the successive strokes of said needle-bar and operative movements of said feed-foot in a predetermined sequence.

5. In a chain stitch sewing machine, and in combination, a reciprocable needle-bar, a feed-foot, and operating mechanism for reciprocating said needle-bar and imparting an operative movement to said feed-foot at each reciprocation of said needle-bar, the said operating mechanism comprising automatic means for producing needle-bar reciprocations and corresponding feed-foot operative movements of two different lengths in a predetermined sequence.

6. A sewing machine according to claim 5, comprising also manually adjustable means for regulating the two said different lengths.

7. In a chain stitch sewing machine, and in combination, a reciprocable needle-bar, a feed-foot, a feed-foot operating member, an eccentric drive member in operative relation to both said needle-bar and feed-foot operating member, a drive shaft carrying said drive member, and

stitch-regulating means for varying the eccentricity of said drive member with relation to the axis of said drive shaft while maintaining a substantially fixed relationship between the movements of said needle-bar and operating member relative to the angular position of said drive shaft.

8. A sewing machine according to claim 7, in which the said stitch regulating means comprises automatic means for varying the eccentricity of said drive member to produce a predetermined sequence of stitches of varying length.

9. In a chain stitch sewing machine, and in combination, a reciprocable needle-bar, a feed-foot, a feed-foot operating member, an eccentric drive member in operative relation to both said needle-bar and feed-foot operating member, a drive shaft carrying said drive member, and stroke-regulating means for varying the eccentricity of said drive member comprising means for moving said drive member transversely and rectilinearly upon said drive shaft.

10. A sewing machine according to claim 9, in which the said stroke regulating means comprises automatic means for varying the eccentricity of said drive member to produce correspondingly varying movements of said needle-bar and said feed-foot operating member in a predetermined sequence.

11. A sewing machine according to claim 9, in which the said stroke regulating means comprises manually adjustable means for setting said drive member in various adjusted positions upon said shaft and automatic means for moving said drive members between predetermined limits with reference to such adjusted positions to produce needle-bar reciprocations of two different lengths and corresponding movements through different distances of said feed-foot operating member in a predetermined sequence.

12. In a chain stitch sewing machine, and in combination, a reciprocable needle-bar, a feed-foot, a feed-foot operating member, an eccentric drive member in operative relation to both said needle-bar and feed-foot operating member and having a slot and a rack upon one side of said slot, a slotted hollow shaft carrying said drive member in transversely slidable relation, an inner shaft within said hollow shaft and having a pinion in mesh with said rack, and stroke regulating means for varying the angular position of said inner shaft with relation to said hollow shaft to vary the eccentricity of said drive member with relation to said hollow shaft.

13. A sewing machine according to claim 12, in which the said stroke regulating means comprises a fixed gear concentric with said hollow shaft and a planetary gear train in mesh with said fixed gear for rocking said inner shaft through a predetermined angle during each rotation of said hollow shaft.

14. In a sewing machine and in combination, a needle-bar, a feed-foot bar, a fabric table, means for reciprocating said needle-bar and feed-foot bar to and away from said fabric table, a feed-foot, and means mounting said feed-foot slidably along and pivotally upon said feed-foot bar in the path of movement of said needle-bar for movement thereby, whereby said feed-foot is positioned with reference to said fabric table in accordance with the thickness of fabric thereon and is forced aside by said needle-bar to impart a feeding movement to fabric upon said fabric table.

15. A sewing machine according to claim 14, in which the said means mounting the feed-foot

upon the feed-foot bar comprises a pin-and-slot connection slanting upwardly toward said needle bar, and the feed-foot comprises a portion engaged by said needle-bar and slanting downwardly toward said needle-bar.

16. In a sewing machine, and in combination, a reciprocable needle, a fabric table cooperating therewith, feeding means for moving fabric along said table, a fabric-foot for holding fabric against said fabric table, a support member inclined downwardly and forwardly toward said fabric table, means for slidably mounting said fabric-foot on said support for movement downwardly and forwardly against the direction of fabric movement, and yieldable means for urging said fabric-foot toward said fabric table.

17. In a chain stitch sewing machine, and in combination, a reciprocable hooked needle, thread handling mechanism cooperating therewith to form a succession of loops and comprising thread holding means positionable to present any of a plurality of different threads to said needle for engagement thereby at each reciprocation thereof, drive means for positioning said thread holding means, and means for adjusting said drive means to present the said different threads to said needle in any of a plurality of different sequences.

18. In a chain stitch sewing machine, and in combination, a reciprocable hooked needle, thread handling mechanism cooperating therewith to form a succession of loops and comprising means positionable to present any of a plurality of different threads to said needle for engagement thereby at each reciprocation thereof, and drive means for positioning said thread holding means comprising a cam having adjustable levels and means for adjusting the levels of said cam to present the said different threads to said needle in any of a plurality of predetermined sequences.

19. In a chain stitch sewing machine, a hooked needle, thread handling mechanism cooperating therewith and comprising a looping member having a central bearing surface for engaging said needle and lateral thread guide portions on opposite sides of said surface, yieldable means for urging said member toward engagement with said needle and pressing said bearing surface against said needle, and machine drive means for moving said member away from said needle into either of two positions on opposite sides of said needle and lying on a line spaced from said needle, so as to bring both said thread guide portions on the same side of said needle when said member is in either of the two said positions, and means for releasing said member to permit said yieldable means to return the same into position engaging said needle.

20. A sewing machine according to claim 19, in which the same machine drive means comprises adjustable means for successively and selectively moving the said member into the said two positions in any of a plurality of predetermined sequences.

21. In a chain stitch sewing machine, a hooked needle, thread handling mechanism cooperating therewith and comprising a looping member having a central bearing surface for engaging said needle and lateral thread guide portions on opposite sides of said surface, relatively flexible spring means for urging said member toward engagement with said needle and relatively stiff spring means for centralizing said member with relation to said needle, and means for moving said member away from said needle into either of two positions on opposite sides of said needle and ly-

ing on a line spaced from said needle so as to bring both said thread guide portions on the same side of said needle when said member is in either of the two said positions, and means for releasing said member to permit said yieldable means to return the same into position engaging said needle.

22. In a chain stitch sewing machine, a hooked needle, thread handling mechanism cooperating therewith and comprising a looping member having a central bearing surface for engaging said needle and lateral thread guide portions on opposite sides of said surface, a flexible strap spring for supporting said member and comprising a relatively long portion for urging said member toward engagement with said needle and a relatively short portion twisted at right angles for centralizing said member, and means for moving said member away from said needle into either of two positions on opposite sides of said needle and lying on a line spaced from said needle so as to bring both said thread guide portions on the same side of said needle when said member is in either of the two said positions, and means for releasing said member to permit said yieldable means to return the same into position engaging said needle.

23. In combination in a sewing machine, a thread supply source, a needle having a hook near an end thereof and a guideway extending longitudinally of said needle from said hook toward the other end of said needle, a member having at one end a channel adapted to receive the barb of said hook, said member being slidably arranged in said guideway and reciprocable to and from a position at which said channel surrounds the barb of said hook and forming with said hook a closable thread receiving opening, means for moving said needle to and from operative relationship with said thread supply source, and means for operating said member to close said hook as it moves away from operative relationship with said thread supply source and to open said hook as it moves toward said thread supply source.

24. In combination in a chain stitch sewing machine, means for forming from thread a succession of loops, said means including a movable means successively engageable with said thread to form loops therefrom and, during each succeeding loop-forming movement, passing through the next preceding loop to thereby provide interengaged loops forming a series of chain stitches, and means controlling said movable means for sequentially varying the effective length of movement thereof to correspondingly sequentially vary the length of said loops.

25. In combination in a chain stitch sewing machine, means for forming from threads a succession of loops, said means including movable means selectively engageable with said threads to form certain of said loops of at least one of said threads and to form certain other said loops of at least one other of said threads and, during each succeeding loop-forming movement, passing through the next preceding loop to thereby provide interengaged loops forming a series of stitches, and means sequentially controlling said movable means for varying the effective length of movement thereof to correspondingly sequentially vary the length of said loops.

26. In combination in a chain stitch sewing machine, means for forming from thread a succession of loops, said means including movable means engageable with said thread to form loops therefrom and, during each succeeding loop-forming movement, passing through the next pre-

ceding loop to thereby provide interengaged loops forming a series of stitches, means controlling said movable means for sequentially varying the effective length of movement thereof to correspondingly sequentially vary the length of said loops, and other means controlling said movable means for predetermining the effective length of movement thereof during the formation of each of said loops to thereby determine the length of each of said loops.

27. In combination in a chain stitch sewing machine, means for forming from thread a succession of loops, said means including movable means engageable with said thread to form loops therefrom and, during each succeeding loop-forming movement, passing through the next preceding loop to thereby provide interengaged loops forming a series of stitches, means controlling said movable means for varying in any of a plurality of sequences the effective length of movement of said movable means to correspondingly vary the length of said loops, and means for selectively setting the controlling means so that the effective length of movement of said movable means and the loops formed thereby correspond to a selected loop-length sequence.

28. In combination in a chain stitch sewing machine, means for forming from thread a succession of loops, said means including movable means engageable with said thread to form loops therefrom and, during each succeeding loop-forming movement, passing through the next preceding loop to thereby provide interengaged loops forming a series of stitches, and stitch-length determining means for producing relative movements between the machine and a fabric being stitched, and means controlling said stitch length determining means for varying the length of relative movements between said machine and fabric in a predetermined sequence and simultaneously controlling said movable means for varying the effective length of movement thereof to correspondingly vary the length of said loops so that the length of the loop for each stitch is substantially equal to the sum of the relative movement between said machine and fabric and the thickness of the fabric.

29. In combination in a chain stitch sewing machine, means for forming from threads a succession of loops, said means including movable means selectively engageable with said threads to form certain of said loops of at least one of said threads and certain other of said loops of at least one other of said threads and, during each succeeding loop-forming movement, passing through the next preceding loop to thereby provide interengaged loops forming a series of stitches, and means selectively controlling said movable means for varying in each of a plurality of sequences the effective length of movement of said movable means to correspondingly vary the length of said loops in loop-length sequences respectively corresponding to the first said sequences.

30. In combination in a chain stitch sewing

65

- machine, means for forming from threads a succession of loops, said means including movable means engageable with a plurality of said threads to form a series of multi-thread loops therefrom and, during each succeeding loop-forming movement, passing through the next preceding multi-thread loop to thereby provide interengaged multi-thread loops forming a series of stitches, and means selectively controlling said movable means for varying the effective length of movement thereof to correspondingly vary the length of said multi-thread loops in a plurality of sequences of loop lengths.
31. In combination in a chain stitch sewing machine, means for forming from threads a succession of loops in a plurality of thread sequences and in a plurality of loop length sequences, said means including movable means selectively engageable with said threads to form certain of said loops of at least one of said threads and certain others of said loops of at least one other of said threads, and, during each succeeding loop-forming movement, passing through the next preceding loop to thereby provide interengaged loops forming a series of stitches, means for selectively controlling the first said means to cause engagement of said movable means with a predetermined number of said threads in any of said plurality of thread sequences, and control means for selectively varying the effective length of movement of said movable means to correspondingly vary the length of said loops in any of said plurality of loop-length sequences.

32. In combination in a chain stitch sewing machine, means for forming from threads a succession of loops, said means including movable means engageable with said threads to form loops therefrom and during each succeeding loop-forming movement, passing through the next preceding loop to thereby provide interengaged loops forming a series of stitches, and means for selectively engaging with said movable means each of a plurality of said threads in a predetermined thread sequence, and control means for sequentially varying the effective length of movement of said movable means to correspondingly sequentially vary the length of said loops.

THOMAS E. MONROE.
